(57) **CLAIM**

The ornamental design for measuring quantity of motion sensor, as shown and described.

DESCRIPTION

FIG. 1 is a top, front and side perspective view of a measuring quantity of motion sensor showing my new design;

FIG. 2 is a front elevation view thereof;

FIG. 3 is a rear elevational view thereof;

FIG. 4 is a side elevational view thereof;

FIG. 5 is an opposite side elevational view thereof;

FIG. 6 is a top plan view thereof;

FIG. 7 is a bottom plan view thereof; and,

FIG. 8 is a bottom plan and side perspective view thereof. The portions shown in broken lines are solely for the purpose of illustrating context only and form no part of the claimed design.
